US00D911329S

(12) **United States Design Patent** (10) **Patent No.:** **US D911,329 S**
(45) **Date of Patent:** **** Feb. 23, 2021**

(54) **LAPTOP COMPUTER**

(71) Applicant: **Samsung Electronics Co., Ltd.**, Suwon-si (KR)

(72) Inventors: **Jusuek Lee**, Suwon-si (KR); **Hyuntaik Lim**, Suwon-si (KR)

(73) Assignee: **SAMSUNG ELECTRONICS CO., LTD.**, Gyeonggi-do (KR)

(**) Term: **15 Years**

(21) Appl. No.: **29/686,152**

(22) Filed: **Apr. 2, 2019**

(30) **Foreign Application Priority Data**

Dec. 24, 2018 (KR) 30-2018-0061328

(51) **LOC (13) Cl.** **14-02**

(52) **U.S. Cl.**

USPC **D14/315**

(58) **Field of Classification Search**

USPC D14/371, 376, 315–327, 479, 150, 168, D14/203.4, 203.6, 247, 331, 345–346, D14/391–399, 401, 429, 434, 440, D14/455–457, 477, 507, 509; D3/900–901; 361/679.08, 679.09, 361/679.11, 679.26, 679.27; D21/324, D21/409, 512, 515; D12/192, 416–418

CPC B41J 5/00; B41J 5/10; B41J 5/12; F16M 11/10; G06F 3/0219; G06F 3/02

(57) **CLAIM**

The ornamental design for a laptop computer, as shown and described.

DESCRIPTION

FIG. 1 is a front perspective view of a laptop computer, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a bottom perspective view thereof.

The broken lines immediately adjacent the shaded areas represent the bounds of the claimed design while all other broken lines are directed to portions of the laptop computer that form no part of the claim; the broken lines form no part of the claimed design.

1 Claim, 8 Drawing Sheets
